UNITED STATES PATENT OFFICE

ARTHUR G. STEVENSON, OF ROCHESTER, NEW YORK

DESIGN FOR A COMBINED PENCIL AND LIGHTER

Application filed November 10, 1930. Serial No. 37,618. Term of patent 7 years.

To all whom it may concern:

Be it known that I, ARTHUR G. STEVENSON, a citizen of the United States, residing at Rochester, in the county of Monroe and State of New York, have invented a new, original, and ornamental Design for a combined Pencil and Lighter, of which the following is a specification, reference being had to the accompanying drawing, forming part thereof.

Figure 1 is an elevation of a combined pencil and lighter, showing my new design.

Figure 2 is an elevation of a combined pencil and lighter, showing my new design and looking at it at right angles to the position illustrated in Figure 1.

I claim:

The ornamental design for a combined pencil and lighter, as shown.

ARTHUR G. STEVENSON.
